DESIGN FOR A COMBINED HANDBAG AND UMBRELLA HOLDER OR SIMILAR ARTI- CLE

Alfred Rajna, New York, N. Y.

Application October 4, 1941, Serial No. 103,636

Term of patent 7 years

To all whom it may concern:

Be it known that I, Alfred Rajna, a former subject of Hungary, who has declared and filed his intention to become a citizen of the United States, residing at 15 East 36th Street, in the city of New York, county of New York, State of New York, have invented a new, original, and ornamental Design for a Combined Handbag and Umbrella Holder or similar article, of which the following is a specification, reference being had to the accompanying drawing, forming part thereof.

Fig. 1 is a front elevational view of a combined handbag and umbrella holder showing my new design;

Fig. 2 is a perspective view showing the front and one end of the bag illustrated in Fig. 1; and

Fig. 3 is a perspective view showing the back and other end thereof.

I claim:

The ornamental design for a combined handbag and umbrella holder or similar article, substantially as shown.

ALFRED RAJNA.
